CLAIM

We claim the ornamental design for a pump component, as
shown and described.

DESCRIPTION

FIG. 1 is a top perspective view of a pump component in
accordance with an embodiment of our new design, illustrating
a portion of an impeller;

FIG. 2 is a front elevation view of the pump component of
FIG. 1;

FIG. 3 is a rear elevation view of the pump component of
FIGS. 1-2;

FIG. 4 is a right-side elevation view of the pump component of
FIGS. 1-3;

FIG. 5 is a left-side elevation view of the pump component of
FIGS. 1-4;

FIG. 6 is a top plan view of the pump component of FIGS.
1-5; and,

FIG. 7 is a bottom plan view of the pump component of
FIGS. 1-6.

The portions shown in broken lines in the figures depict
unclaimed environmental subject matter, are for illustrative
purposes only, and form no part of the claimed design.
Similarly and where applicable, unshaded portions that
appear between broken lines or beyond boundary or break
lines in the figures form no part of the claimed design and
indicate that a specific width, height and/or length forms no
part of the claimed design.
